UNITED STATES PATENT OFFICE.

EDWARD PALLISER, OF WEST KENSINGTON, COUNTY OF MIDDLESEX,
ENGLAND.

PROJECTILE.

SPECIFICATION forming part of Letters Patent No. 275,258, dated April 3, 1883.

Application filed June 1, 1882. (No model.) Patented in England April 8, 1882, No. 1,703.

To all whom it may concern:

Be it known that I, EDWARD PALLISER, a citizen of England, residing at West Kensington, in the county of Middlesex, England, have 5 invented a new and useful Improvement in Projectiles for Ordnance, (for which I have obtained provisional protection in Great Britain, No. 1,703, dated April 8, 1882,) of which the following is a specification.

10 My invention has reference to a construction of projectiles for ordnance with ribbed head, for which an application for Letters Patent has been filed, of equal date herewith, in the name of John Palliser. In the specification 15 to the said application is described the shrinking of a wrought-iron or steel ring or short jacket onto the cylindrical body of the projectile behind the ends of the ribs. It has been found that the impact of the shoulder of 20 this tightly-fixed ring or short jacket against the armor-plates as the projectile penetrates, in some instances when the projectile is made of chilled cast-iron, causes this to snap asunder at that point.

25 According to my present invention I obviate this defect by constructing the body of the projectile of a slightly-tapering diameter toward the rear end, and shrinking thereon a jacket extending the whole length, or nearly so, of the 30 body, and fitting with a correspondingly-tapered inner surface thereon. By this arrangement the jacket will strengthen the body of the projectile against fracture by concussion upon the impact of the head against the armor-plate, and while the head is passing through; 35 but when the projectile has penetrated so far that the front edge of the jacket comes in contact with the armor-plate the jacket will be readily pushed off the body of the projectile 40 on account of the tapering fit of the two parts, and thus the fracture of the body will be prevented. I strengthen the projectile against fracture by providing it with an inner wrought-iron or steel casing, or by binding it round 45 with steel ribbon or wire, and in this case the inner casing would fit with a cylindrical surface onto the cylindrical body of the projectile, and would be formed with a tapering outer surface, upon which the taper outer jacket would 50 be shrunk. In this case, also, the outer jacket

may be reduced in length, so as only to constitute a taper bearing-ring.

Figure 1 of the accompanying drawings shows one arrangement of the projectile constructed according to my invention. A is the conoidal head, having radial ribs B, terminating at the springing of the conoidal curvature. Beyond this point the body C of the projectile is reduced in diameter, as shown, the part from C' to C² being cylindrical, and upon this is shrunk 55 the jacket or casing D, having an internal configuration corresponding to that of the body, while its outer surface, being at its front end equal in diameter to the base of the head, is made to taper to a smaller diameter at the rear 60 end. Upon the tapering surface thus formed is now shrunk the outer jacket, E, having a correspondingly-tapering inner surface, while its outer surface is cylindrical, being at the two ends made nearly equal in diameter to the 65 bore of the gun, such enlarged end portions constituting annular rings or bands corresponding in diameter to that of the outer 70 edges of the ribs B, so that these will not injure the bore of the gun on firing. The central 75 portion of the jacket between such rings or bands is depressed, so that the rings or bands alone rest against the bore of the gun, the forward one preventing the ribs B from coming in contact with and injuring the bore. As before described, the outer jacket, E, will be readily stripped off on the projectile passing through the armor-plate, while the inner jacket, D, being flush with the diameter of the head, will remain on the body and strengthen it 80 against fracture. The contact-surfaces of C and D are for this purpose made rough, while those of D and E are made smooth. F is the gas-check ring, of soft metal, which is expanded 85 by the pressure of the gases so as to fit tightly 90 against the bore of the gun and prevent the escape of gases past the projectile.

Fig. 2 shows a modification in which the inner jacket is dispensed with, the surface of the body C being itself made of the requisite taper 95 to fit the taper jacket E. It is preferred, however, to use the inner jacket, D, or, in lieu thereof, to bind the body C round with a sheathing of steel ribbon or wire in order to strengthen it.

Fig. 3 shows another modification, in which the inner jacket or sheathing is provided with an outer jacket composed of rings or bands G G', interiorly tapered and shrunk on the respective ends of the inner jacket, the ring or band G serving to prevent the ribs B from coming in contact with and injuring the bore of the gun when firing, both rings or bands, however, being stripped or driven off of the inner jacket by contact with the armor-plate.

Although I have shown and described my invention as applied to a projectile having a ribbed head, it will be obvious that the invention is applicable to other or ordinary forms of projectiles.

Having thus described the nature of my invention and in what manner the same is to be performed, I claim—

The combination, with a projectile, of an inner jacket or sheathing having a tapering outer surface and fixed upon the projectile-body, and an outer jacket tapered interiorly and secured upon the inner jacket or sheathing, but capable of being stripped therefrom by contact with an armor-plate or other object, leaving the inner jacket intact to strengthen the projectile-body against fracture, substantially as described.

In testimony whereof I have signed my name to this specification, in the presence of two subscribing witnesses, this 9th day of May, A. D. 1882.

EDWARD PALLISER.
